UNITED STATES PATENT OFFICE.

THOMAS B. ATTERBURY, OF PITTSBURG, PENNSYLVANIA.

DESIGN FOR A DISH-COVER.

SPECIFICATION forming part of Design No. 19,249, dated August 6, 1889.

Application filed July 2, 1889. Serial No. 316,340. Term of patent 7 years.

To all whom it may concern:

Be it known that I, THOMAS B. ATTERBURY, a citizen of the United States, residing at Pittsburg, in the county of Allegheny and State of Pennsylvania, have invented and produced a new and original Design for Dish-Covers; and I do hereby declare the following to be a full, clear, and exact description of the same, reference being had to the accompanying drawing, forming a part thereof.

In the drawing I have shown a dish-cover in perspective having a lion mounted thereon.

The cover, which is by preference elliptical and also of oval shape, has formed around its base a border consisting of short upwardly-extending ribs or flutings, above which the top of the mound or oval portion is made in imitation of trampled grass or turf, and on which is a lion in an attitude of repose with the head raised.

A indicates the main body of the cover,

which has the short longitudinal flutings or ribs *a* extending around the base and the upper portion *b* roughened to represent long grass. On the top of the cover is formed the handle *B*, which represents a lion squatting or lying down with the head erect.

What I claim is—

The design for a dish-cover, as shown and described, the same consisting of an oval or mound shaped cover *A*, having short longitudinal flutings or ribs extending around its base, above which it is made in representation of turf, the handle portion *B* representing a lion lying down with head erect.

In testimony whereof I affix my signature in presence of two witnesses.

THOMAS B. ATTERBURY.
